UNITED STATES PATENT OFFICE.

ROSE BINNER SCOGNAMILLO, OF NEW YORK, N. Y.

FORM-FITTING MOLD.

Application filed May 14, 1924. Serial No. 713,228.

This invention is a form fitting mold to be used as a substitute for corsets.

The primary object of the invention is to provide a support for the natural figure, and a foundation for the draping of garments, conforming to the figure, and preserving definition of the natural lines thereof in the normal movement of the body, so constructed and arranged that any displacement of the flesh during such movement is in the direction of the length of the body.

Corsets are designed to shape the figure by displacing portions of the body in various directions to attain the end desired. Such devices are usually of rigid or semi-rigid material, clasp the figure closely, and shape the body by flesh displacement to the form desired.

In the present invention the form-fitting mold is shaped to fit the natural figure of the wearer and to touch lightly throughout the entire area thereof, but without undue pressure in any part, and it is so constructed that the natural lines of the figure are preserved in the normal movements of the body.

With this object in view, I provide a mold of tubular formation, and of a material elastic circumferentially in order that it may be slipped upon the body. The normal contraction above the hips partially supports the mold, but I do not rely upon this for the sole support. A form fitting brassière is provided, constructed and arranged to support the bust and retain it in its natural lines, and the brassière supplements the action of the mold and cooperates therewith, in preserving the natural body lines, and serves also as a support for the mold, being in turn supported from the shoulders of the wearer.

The material of the improved mold is soft and pliable, and to a limited extent stretchable in every direction, but in certain directions where flat lines are desired, with free movement, I provide means in the form of non-elastic inserts or bridge pieces to define and preserve such lines. In other locations where a firmer support than merely a non-elastic insert is desirable, as for instance at the front, I arrange semi-rigid stays, and the stays are extended well above the waist line to support the diaphragm and the organs just beneath the same and connected therewith.

In the drawings forming a part hereof:

Fig. 1 is a front view of the improved form fitting mold in use.

Fig. 2 is a side view.

Fig. 3 is a rear view.

Fig. 4 is a perspective plan view of the brassière spread out.

Fig. 5 is a similar view of the mold.

In the present embodiment of the invention the improved mold or garment is of tubular formation, and is composed of four pieces of loosely woven or knit material, which is elastic in one direction, in the present instance circumferentially of the tubular structure. The four pieces are cut to such measure, that when connected in the manner to be presently described, they will fit the form of the wearer, touching lightly throughout the area of the garment, but without undue pressure at any point.

The garment is composed of a back piece 1, two similar side pieces 2, and a front piece 3. Each of the pieces 1, 2 and 3, extends the full length of the garment from the top to the bottom thereof, and their adjacent edges are connected by non-elastic tapes 4 and 5, the tapes 4 connecting the back with the side pieces, while the tapes 5 connect the side pieces with the front piece. Each of the pieces has a selvage edge 6 at its upper end and a similar edge 7 at its lower end, and the said edges 7 of the four pieces are connected at the lower end of the mold in a continuous and gracefully curved line, as shown in Fig. 5.

The side pieces 2 are woven in such manner that they narrow toward the front piece 3, as clearly shown in Fig. 5, this narrowing being produced by the formation of darts 5^a woven in the material. Since the four pieces are substantially the same length, the narrowing of the side pieces and the connection of the front piece with the selvage edge 7 in alignment with the selvage edges of the side pieces, causes the upper end of the front piece 3 to extend well above the upper edges of the side pieces, as shown in Fig. 5. This would leave a considerable portion of the upper end of the front piece disconnected at its side edges from the side pieces, and strips 15 of elastic material are arranged between the tapes 4 and the tapes 5, the upper edges of the strips 15 being in effect continuations of the selvage edge 6 of the back piece.

At the back of the garment, it is desirable

to have straight lines, without interfering with the movement of the parts, and I insert at this point a non-elastic bridge piece 8 extending the full length of the back piece 5 between the selvage edges and secured on the inner face thereof by means of non-elastic tapes 9. This prevents stretching of that portion of the material between the tapes 9 circumferentially of the garment. The 10 tapes 4 and 5 which connect the back, the side and the front pieces are also non-elastic and prevent stretching of the material along such lines. It will be noticed, referring to Fig. 2, that the tapes 4 which connect the 15 back and side pieces are at the sides of the body, and the said tapes preserve the lines of the figure at the sides.

At the front a firmer support than merely a non-elastic insert is desirable to support 20 the diaphragm and organs adjacent thereto, and at this point I arrange a series of semi-rigid stays, the stays being arranged in pairs indicated at 10 and 11, respectively. The stays 10 extend from the selvage edge 25 6 of the front piece about half the length of the said piece, and are arranged in sheaths in the tapes 5. The stays 11 are of the same length as the stays 10, and are held in sheaths in non-elastic tapes 12, which are secured to 30 the inner face of the front piece 3, at the center thereof, the said tapes extending the full length of the front piece between the selvage edges 6 and 7.

Hose supporting straps 13 may be connected with the selvage edge 7 of the side pieces 2, and with the ends of the tapes 9, and buttons 14 are connected with the tapes 9 and with the tapes 5 and 12 near the tops thereof for a purpose to be presently described.

The contraction at the upper end of the garment as a whole, causes it to embrace the body lightly just above the hips, and this natural contraction aids in the support of 45 the garment, but I do not rely solely upon the same.

An additional and principal support is provided in the shape of a brassière. This 50 is composed of four pieces of suitable material, indicated at 16 and 17, respectively. The pieces 16 are suitably shaped by darts 18 to support the bust in its natural position and maintain its form, and they are of an aggregate length to extend across the front 55 of the chest from one side line to the other. They are connected at the center of the front as indicated at 19 by a line of stitching or in any other suitable manner, and the pieces 17 are connected to the outer ends of the pieces 16, by similar lines of stitching 20. Shoulder straps 21 are connected with the pieces 16 and 17 respectively, for supporting the brassière and the mold from the shoulders, and the brassière is held in place on 60 the body by a strap 22 of elastic which is ar- 65

ranged between the free ends at the lower edge thereof, as shown in Fig. 3.

Straps 23 depend from the pieces 17 near their outer ends, and the said straps are designed to engage the buttons on the tapes 70 9. A strip 24 is connected with the lower edges of the pieces 16 at the center of the brassière, and this strip has button holes for engaging the buttons on the tapes 5 and 12. The strap 22 carries buttons which are 75 engaged by button holes at the opposite end of the brassière. It will be noticed, referring to Figs. 1 and 3, that the brassière is cut low enough at the front and is open low enough at the back, so that no part thereof 80 will be exposed when evening dress is worn.

Referring to the drawing, it will be noticed that the lower edge of the brassière is spaced above the upper edge of the mold, a distance such that a zone of the body of 85 considerable width is free from both. This zone insures that only the flesh of the wearer will be perceptible through the outer garments to a dancing partner, for instance.

The improved mold is shaped to fit the 90 body from a point just above the hips to just below the perineum, although it is obvious that it may be of any desired length. The 95 four pieces which compose the garment extend the full length thereof, and since all are of flexible material, the entire garment is freely flexible, conforming to the movement of the body in every position, and with no discomfort to the wearer, preserving the 100 natural youthful form. While extremely 105 flexible in every part, except at the top of the front, the garment yet offers sufficient support to the body, and forms a sufficiently firm foundation for the draping of garments. The open or porous mesh weave 110 provides for ventilation, and the only part of the garment which is even semi-rigid, is at the top of the front, as before stated. Since the garment is elastic and resilient circumferentially, minor changes in weight will 115 not effect the fit thereof.

It will be noticed, referring to Fig. 4, that strap 22 is connected to the lace with which the edge of the brassière is trimmed. The strip 24 is, however, connected directly to 115 the body of the brassière, the lace trimming dropping in front of the strip. The button holes which engage the buttons on the ends of the strap 22 are in the lace trimming at the opposite end of the brassière.

While the invention is shown in a preferred form, it will be apparent that changes and modifications may be made in the structure disclosed without departing from the spirit of the invention as defined in the appended claims.

What I claim is:—

1. A tubular form fitting garment of the step-in type, composed of a front, a back, and side pieces, all of woven elastic, said 130

pieces connected at their adjacent edges by non-elastic strips, and the front piece of a length to extend well above the top of the garment when in place and stayed at its side edges and intermediate its side edges by semi-rigid stays extending downwardly from the upper portion thereof, said front piece and the edges providing a straight front effect, and a non-elastic bridge piece at the back, connected to the back piece at the side edges of the bridge piece by non-elastic tapes, said bridge piece at its top being relatively narrow as regards the back piece, and at its bottom relatively wide to provide for a flat hip effect.

2. A tubular form fitting garment of the step-in type, composed of a front, back and side pieces all of woven elastic, the front relatively narrow and decreasing in width from the top thereof, non-elastic tapes connecting the several pieces at their adjacent edges, the pieces having selvage edges at the top and bottom of the garment and so connected together that at the bottom of the garment the selvage edges are in alinement, and at the top of the garment the selvage edges of the back and side pieces are in alinement, the side pieces narrowed toward the front piece whereby the upper end of the front piece is extended well above the side and back piece to support the front of the body above the waist line, and the lower

end is raised above the lower ends of the side pieces.

3. A tubular form fitting garment of the 35 step-in type, composed of a back piece, side pieces and a front piece all of woven elastic and connected together at their adjacent side edges by non-elastic connections, the ends of the garment of reduced cross section and 40 the garment between the said ends provided with darts to constrain the garment to fit closely over the hips from a low waist line just above the hips to just below the perineum, the front piece of the garment of 45 greater length than the side and back pieces, and connected to the side pieces to extend above the remaining pieces, and stayed over a portion at the upper end thereof to provide a flat front effect, and a brassière of a 50 circumferential length such that when in place the ends at the back will be spaced well apart from each other, said ends connected at their lower corners by a flexible strap, shoulder straps extending from the 55 upper corners of the said ends to the front of the brassière, and means to connect the brassière to the garment by the front piece, and at each end of the brassière at the back.

Signed at New York, in the county of 60 New York and State of New York this 3rd day of May, A. D. 1924.

ROSE BINNER SCOGNAMILLO.
